UNITED STATES PATENT OFFICE.

EDWARD F. W. KAISER, OF ST. LOUIS, MISSOURI.

RACK FOR PRINTING-CHASES AND THE LIKE.

1,107,960.

Specification of Letters Patent. Patented Aug. 18, 1914.

Application filed March 21, 1914. Serial No. 826,270.

To all whom it may concern:

Be it known that I, EDWARD F. W. KAISER, a citizen of the United States, residing at the city of St. Louis, State of Missouri, have 5 invented a certain new and useful Improvement in Racks for Printing-Chases and the like, of which the following is a specification, reference being had to the accompanying drawings, forming a part hereof, in 10 which—

Figure 1 is a plan view of a rack embodying my invention; Fig. 2 is a side elevational view of the same, partly in longitudinal section on the line 2—2, Fig. 1; Fig. 3 is an 15 end elevational view, partly in section; Fig. 4 is a side elevational view, slightly enlarged, of one of the printing-chase engaging or gripping-arms; and Fig. 5 is a front 20 elevational view, partly in section and also slightly enlarged, of one of the printing-chase engaging or gripping-arms.

This invention relates to a certain new and useful improvement in racks for printing-chases and the like, the objects of my 25 present invention being to provide a simple, inexpensive, strong, and durable rack preferably in the form of a skeleton or open frame in which printing-chases and the like to a relatively large number and of various 30 heights or sizes may be readily placed and conveniently, accessibly, and compactly stored when not in use and from which the chases may be severally easily and quickly removed when required, a large saving of 35 floor-space and time being thereby had, and to improve generally upon racks of the kind stated.

With the above and other objects in view, my present invention resides in certain novel 40 features of construction, arrangement, and combination of parts, all as will hereinafter be described and afterward pointed out in the claim.

Referring to the accompanying drawings, 45 in which like reference characters refer to like parts throughout the several views, A indicates the body-portion of my new rack, which is preferably in the form of an up-standing open or skeleton rectangular frame 50 made up of or comprising standards or posts 1 preferably metallic pipe-bars integrally or otherwise suitably provided at their lower ends with feet 2 adapted to rest upon a floor or other place of support, horizontally-disposed 55 longitudinal connecting members 3—3, and horizontally-disposed lateral or

cross members 4—4 connecting members 3—3 and 4—4, which are likewise preferably metallic pipe-bars, being preferably fixed, as by means of joint or corner members 5, to the upper ends of posts 1, as seen particularly in Figs. 1 and 2.

Fixed or otherwise suitably secured upon posts 1 adjacent their lower ends, are inwardly-presented brackets 6, upon which is 60 fixed or otherwise secured a preferably metallic flooring 7 longitudinally provided on its upper face with a series or plurality of channels or slide-ways 8 adapted to endwise 65 slidably receive and accommodate printing-chases or the like C. Also fixed or otherwise suitably secured upon posts 1 adjacent their lower ends, are outwardly-presented brackets or bearing-members 9, upon which are rotatably mounted and supported at the 70 opposite ends of frame A horizontally-disposed rollers 10—10 extending transversely of frame A, the plane of rollers 10—10 being preferably slightly above the plane of the base of channels 8, whereby the chases 80 C may be slidably placed or inserted into upright position in, or removed from, channels 8 with little friction, as will be well understood.

Extending transversely across frame A at 85 a suitable distance inwardly from opposite end or cross bars 4—4, are bars 11—11, each of said bars 11—11 having its opposite ends suitably fixed or secured, as by means of connecting-members 16, to longitudinal frame- 90 member or bars 3—3, as clearly seen in Fig. 1. Loosely pivoted on each of said bars 11 is a series or plurality of independently swingable preferably metallic arms or members 12, the number of arms 12 on each bar 95 11 preferably corresponding to the number of channels 8 in flooring 7. At its outer or free end, each arm 12 has pivotally connected thereto, as by means of a pin or bolt 13, and carries a shallow substantially U-shaped 100 member 14 (shown clearly in Fig. 5) having its legs presented outwardly and being adapted to grip or engage a chase C when chase C is endwise resting or supported in a channel 8 of flooring 7 to endwise 105 firmly hold the chase in upright position, as seen in Figs. 2 and 3.

Normally, as when in inoperative position, arms 12 are preferably swung outwardly to rest adjacent their outer or free ends on 110 frame cross-bars 4—4. A printing-chase or similarly shaped article C being now slid-

ably inserted or moved endwise over a roller 10 into a channel 8, the corresponding arm 12 is pivotally moved or swung from its said normal position inwardly to bring its said 5 pivoted or swingable chase-engaging member 14 into operative position relatively to the chase, member 14, when brought to such position, neatly gripping the chase at its margin, as seen clearly in Fig. 2, and thereby 10 firmly holding the chase endwise in upright position in the rack. Should the chase be of extremely small size, that is to say, the smallest size which the particular rack is 15 designed to accommodate, the arm 12, when in operative or chase-engaging position, will project downwardly from bar 11 at approximately right angles to frame-members 3—3, as illustrated in Fig. 2; with a chase of 20 larger size, the arm 12, when in chase-engaging position, will project obliquely downwardly from bar 11 at an angle less than a right angle to frame-members 3—3, as also illustrated in Fig. 2. Chase-gripping members 14, being freely swingable on their 25 carrying-arms 12, will occupy a downwardly-presented position with their legs at right angles to frame-members 3—3 and thus grip the particular chase irrespective of the size or height thereof when the chase 30 is supported as described in a channel 8. Frame A being open-ended and provided as described with a plurality of series or sets of arms 12, it will be evident that chases C may be insertibly fitted thereinto from 35 either end and held endwise in upright position by the arms 12 and their carried members 14 of the adjacent series or set, the capacity of the rack being accordingly increased and determinable only by the size 40 of frame A and the number of channels 8 and arms 12 thereof. To remove a chase C from the rack, arm 12 and its chase-gripping member 14 are preferably first swung

upwardly and outwardly to normal position, when, as will be obvious, the chase is free 45 to be slidably taken from its supporting channel 8. As seen particularly in Fig. 5, each arm 12 is preferably provided at its rear or pivoted end with a widened-bearing, as at 15, on its hinge-bar 11, whereby the 50 free or outer end of the arm is held from swaying laterally relatively to bar 11, thus increasing the rigidity of the support rendered on chases C by members 14 when engaging therewith. 55

I am aware that minor changes in the construction, arrangement, and combination of the several parts of my new rack may be made and substituted for those herein shown and described without departing from the 60 nature and principle of my invention.

Having thus described my invention, what I claim and desire to secure by Letters Patent is:

In a rack of the kind stated, the combination with a plurality of standards and longitudinally-extending connecting members therebetween, of a transverse bar fixed at its ends on said connecting-members, a plurality of chase-engaging arms loosely pivoted at one end on said bar, and a second transverse bar also fixed at its ends on said connecting-members, said second transverse bar being spaced from said first transverse bar and providing a fixed support for the 70 free ends of said arms when the same are swung into inoperative position; substantially as described. 75

In testimony whereof, I have signed my name to this specification in the presence of 80 two subscribing witnesses.

EDWARD F. W. KAISER.
